(57) **CLAIM**

The ornamental design for a mini projector, as shown and described.

DESCRIPTION

FIG. 1 is a perspective upper front and left View of a mini projector;

FIG. 2 is a front View thereof;

FIG. 3 is a rear View thereof;

FIG. 4 is a top View thereof;

FIG. 5 is a bottom View thereof;

FIG. 6 is a right View thereof;

FIG. 7 is a left View thereof;

FIG. 8 is a perspective left View of a portion of the mini projector, showing, in particular, a sliding switch of the mini projector in a larger scale;

FIG. 9 is a perspective left and rear View of a portion of the mini projector, showing, in particular, the sliding switch on the left side and a socket on the rear side of the mini projector;

FIG. 10 is a perspective front and left View of a portion of the mini projector, showing, in particular, the objective lens and a front part of a gap in the housing of the mini projector in a larger scale;

FIG. 11 is a perspective upper front and right View of a portion of the mini projector, showing, in particular, the objective lens and a front part of the gap in the housing of the mini projector as well as four control knobs;

FIG. 12 is a perspective top View of a portion of the mini projector, showing, in particular, a portion of the gap in the housing of the mini projector and a socket located on the lower side of the gap as well as a portion of the four control knobs; and,

FIG. 13 is a perspective View of a portion of the mini projector along the gap of the mini projector, showing the lower side of the gap.

It is to be noted that FIGS. 8-13 are detail views. The detail views show portions of the mini projector on a larger scale.
